ATTORNEY

UNITED STATES PATENT OFFICE.

JAMES M. CUMMING, OF NEWARK, NEW JERSEY.

BOTTLE-STOPPER.

No. 824,913.

Specification of Letters Patent.

Patented July 3 1906.

Application filed January 16, 1906. Serial No. 296,261.

To all whom it may concern:

Be it known that I, JAMES M. CUMMING, a citizen of the United States, residing at Newark, in the county of Essex and State of New

5 Jersey, have invented certain new and useful Improvements in Bottle-Stoppers; and I do hereby declare the following to be a full, clear, and exact description of the invention, such as will enable others skilled in the art 10 to which it appertains to make and use the same, reference being had to the accompanying drawings, and to figures of reference marked thereon, which form a part of this specification.

15 This invention has reference generally to improvements in stoppers for bottles; and the invention relates more particularly to a novel form of stopper and a locking mechanism connected therewith which can be 20 brought in holding or locked engagement with a portion of the bottle when the stopper is inserted in the mouth of the bottle, the arrangement of the parts of the locking mechanism being such that the stopper can 25 not be withdrawn from the mouth of the bottle except by the proper person provided with a key for the manipulation of the locking mechanism.

The principal object of my present invention is to provide a simple, neat, and easily-manipulated stopper which is to be inserted in the ordinary manner in the mouth of the bottle, but when once inserted is immediately secured in its non-removable position 35 to prevent tampering with the contents of the bottle or to avoid accidents by mistaking the poisonous contents of the bottle for the non-poisonous contents of another bottle.

In other words, the purpose of the invention 40 is to provide a positive safeguard against removal of the stopper from the mouth of the bottle except by the person entrusted with the key for actuating the locking mechanism with which the stopper is provided.

45 Other objects of this invention not at this time more particularly mentioned will be clearly understood from the following detailed description of the same.

The invention consists, primarily, in the 50 novel stopper and locking mechanism combined therewith hereinafter set forth; and, furthermore, this invention consists in the novel arrangements and combinations of the devices and parts, as well as in the details of 55 the construction of the same, all of which

will be hereinafter more fully set forth and then finally embodied in the clauses of the claim which are appended to and which form an essential part of this specification.

The invention is clearly illustrated in the accompanying drawings, in which—

Figure 1 is a sectional representation of the neck and mouth portion of a bottle and an elevation of a stopper made according to the principles of my present invention; and Fig. 65 2 is a transverse section of the said parts, both of said views showing the locking mechanism with which the stopper is provided in its locked or holding engagement with an inner annular recess within the neck of the 70 bottle. Fig. 3 is a section similar to that shown in Fig. 2, but illustrating the locking mechanism in its unlocked relation with the said annular recess when actuated by means of a key; and Fig. 4 is a transverse vertical 75 section of the stopper, taken on line 4-4 in Fig. 1 and looking in the direction of the arrow X. Fig. 5 is a view of a key which is used for the manipulation of the locking mechanism shown in said Figs. 1 to 4, inclusive. 80

Similar characters of reference are employed in the said above-described views to indicate corresponding parts.

Referring now to the said drawings, the 85 reference character 1 indicates the neck portion of any suitable bottle with which my novel form of combined stopper and locking mechanism is to be used. One form of such stopper is illustrated in Figs. 1 to 4, inclusive, 90 the same comprising a suitably-shaped hollow or chambered stopper-body 2, which is preferably provided with a closed bottom 3. Surrounding the outer cylindrical surface and the bottom 3 of said stopper-body 2, 95 which is preferably made of metal or other suitable hard material, is a covering or shell 4, made of cork, rubber, or other suitable resilient material, adapted to be brought in contact with the inner surface of the neck 100 and mouth of the usual forms of bottles. The upper marginal edge portion of said covering or shell 4 is fitted, preferably, against an annular shoulder or offset 5 of the said stopper-body 2, the latter then being preferably formed with a contracted neck portion 6, which is formed with an open and outwardly-flaring portion or mouth 7 for the insertion and proper arrangement of the 105 parts within the hollow or chambered stop- 110

per. This open and outwardly-flaring portion or mouth after the mechanism has been assembled is made to receive a semispherical or other suitably-shaped cap or cover, as 8, which is rigidly fixed in place against removal from the stopper-body by means of pins 9 or any other well-known fastening means.

Pivottally arranged upon pins 10, held in 10 suitably-disposed ears or lugs 11, preferably within the contracted neck portion 6 of the stopper, are oscillating arms 12, each arm 12 being provided at its lower part with a holding member or bolt 13, each member or bolt 15 13 being made with a chamfered or inclined edge 14. When in their normal initial positions, a spring 15, supported upon studs or lugs 16 upon the lower portions of said arms 12, causes the oppositely-projecting holding 20 members or bolts 13 to be forced in opposite and outward directions immediately into and through the oppositely located and registering openings or holes 17 and 18 in the stopper-body 2 and the covering or shell 4, 25 respectively, in the manner clearly illustrated in Fig. 2 of the drawings. The upper portions of the said arms 12 extend into the chamber formed by the mouth 7 and the cap or cover 8, being respectively located in 30 close proximity to each other and upon opposite sides of a key-receiving stem or post 19, said stem extending across the said chambered portion and terminating directly back of a suitable keyhole 20, as clearly shown in 35 Fig. 4 of the drawings. When the said arms 12 and their parts are in their normal initial positions, (indicated in said Fig. 2 of the drawings,) the stopper can be readily inserted in the mouth of the neck of the bottle, the 40 chamfered or inclined edges 14 of the bolts or holding portions 13 readily riding over the edge of the mouth of the bottle and becoming depressed while passing downwardly within the neck of the bottle until an annular depression 21 within the neck is reached, 45 into which the holding members or bolts 13 are immediately forced by the action of the spring 15, and whereby the stopper is locked in its closing position within the neck of the 50 bottle against removal therefrom until the two arms 12 and their parts are brought into the positions shown in Fig. 3 of the drawings by the insertion of a key, as 22, (see Fig. 5,) into the keyhole 20 and upon the stem or 55 post 19. When the key is turned in the usual manner, its tongues 23 are rotated between the upper and closely-located end portions of the arms 12 and in engagement therewith, thereby moving said end portions 60 farther apart, and consequently withdrawing the holding members or bolts 13 from their locking or holding engagement with the annular recess or depression 21, bringing the parts in the positions shown in Fig. 3 of the 65 drawings, and the stopper can then be easily

withdrawn from the mouth of the bottle. As soon as the key is removed the parts assume their normal initial positions, (indicated in said Fig. 2,) when the stopper is once more ready for use in closing the mouth and neck 70 of the bottle.

To provide a safeguard against using any form of key for the manipulation of the locking mechanism of the stopper, the key 22 is provided with several variously-disposed 75 tongues 23, having the spaces 24 between them, and within the cover or cap 8 is a baffle-plate 25, which is made in its edge with suitably-formed slots 26 and tongues 27, which correspond with the tongues 23 and 80 intermediate spaces 24 of the key 22, so as not to interfere with the turning of the key, but will serve as a means to prevent a person using any other key for the manipulation of the arms 12 of the locking mechanism which 85 is concealed within the body of the stopper.

From the foregoing description of my present invention it will be clearly seen that I have devised a simply-constructed stopper and locking mechanism which can be used 90 with a bottle in the usual manner, but can be withdrawn only by the person carrying the right key, so as to avoid the stealing of or the tampering with the contents of the bottle, or when used with bottles containing 95 poisonous matter it minimizes the danger of making mistakes, which would otherwise result in serious consequences.

I claim—

1. A chambered stopper for bottles, comprising a stopper-body formed with bolt-receiving openings, a contracted neck, an open and outwardly-flaring portion, a cap or cover on said outwardly-flaring portion, means for rigidly securing said cap or cover upon said outwardly-flaring portion, said outwardly-extending portion being provided with a key-hole, a pair of pivot-lugs in the said contracted neck, an arm pivotally connected with each lug, a bolt upon each arm extending into a bolt-receiving opening, a spring arranged between the lower portions of said arms, and a key-receiving means between the upper portions of said arms for the reception of a key for actuating said arms, substantially as and for the purposes set forth.

2. The herein described stopper for bottles, comprising a stopper-body having a closed bottom and an annular shoulder, a resilient covering or shell surrounding said body and its bottom, said body and covering being provided with registering bolt-receiving openings, a contracted neck, an open and outwardly-flaring portion, a cap or cover on said outwardly-flaring portion, means for rigidly securing said cap or cover upon said outwardly-flaring portion, said outwardly-extending portion being provided with a key-hole, a pair of pivot-lugs in said contracted neck, an arm pivotally connected with each

lug, a bolt upon each arm extending into the registering bolt-receiving openings of said stopper-body and covering, a spring arranged between the lower portions of said arms, and a key-receiving means between the upper portions of said arms for the reception of a key for actuating said arms, substantially as and for the purposes set forth.

In testimony that I claim the invention set forth above I have hereunto set my hand ¹⁰ this 11th day of January, 1906.

JAMES M. CUMMING.
